(57) **CLAIM**

The ornamental design for a frame for sliding doors and walls, as shown and described.

DESCRIPTION

FIG. 1 is a cross sectional view taken along line 1—1 of FIG. 5.

FIG. 2 is a front perspective view of the design of FIG. 1.

FIG. 3 is a rear perspective view of the design of FIG. 1.

FIG. 4 is a front view of the design of FIG. 1.

FIG. 5 is a rear view of the design of FIG. 1.

FIG. 6 is a left side view of the design of FIG. 1; and,

FIG. 7 is a right side view of the design of FIG. 1.

The claimed design is broken in the center to indicate indeterminate length.
